DESIGN FOR A LAMP SHADE

Oscar Walter Johnson and Carl H. Johnson,
Chicago, Ill.

Application June 8, 1933, Serial No. 48,349

Term of patent 3½ years

To all whom it may concern:

Be it known that we, OSCAR WALTER JOHNSON and CARL H. JOHNSON, citizens of the United States, residing at Chicago, in the county of Cook and State of Illinois, have invented a new, original, and ornamental Design for a Lamp Shade, of which the following is a specification, reference being had to the accompanying drawing, forming a part hereof.

Figure 1 is a front elevation.

Figure 2 is a sectional view of one side of the shade illustrated in Figure 1.

The basic sheet of material is translucent, the lines of division being opaque and having a metallic appearance. The material forming these lines is placed on the outer surface of the basic sheet of material so that the lines stand out from the outer surface of the basic sheet.

What we claim is:

The ornamental design for a lamp shade, as shown and described.

OSCAR WALTER JOHNSON.
CARL H. JOHNSON.
